UNITED STATES PATENT OFFICE.

S. MORRIS LILLIE, OF PHILADELPHIA, PENNSYLVANIA.

APPARATUS FOR TREATING GOLD, SILVER, AND OTHER ORES.

SPECIFICATION forming part of Letters Patent No. 241,679, dated May 17, 1881.

Application filed February 16, 1881. (No model.)

To all whom it may concern:

Be it known that I, S. MORRIS LILLIE, a citizen of the United States, and a resident of the city of Philadelphia, in the county of Philadelphia and State of Pennsylvania, have invented new and useful improvements in apparatus for subjecting gold, silver, and other ores to the chemical and disintegrating, separating, and reducing actions of hydrocarbon gases, of which the following is a specification, reference being had to the accompanying drawings and letters of reference thereon.

The nature of my said invention and improvements consists, first, of the hereinafter described apparatus for subjecting ores to the chemical and comminuting action of the gases resulting from the destructive distillation of bituminous coal or other carbonaceous matters, consisting of a series of approximately-verti-
cal retorts for holding the carbonaceous matters from which the gases are to be distilled, and the ores to be subjected to the action of the same ranged in the fire-chamber of a kiln on each side of a central fire-box, each of the said retorts projecting through the roof of the kiln and passing with a curve through one of the side walls of the same, near the bottom of the fire-chamber, the upper and lower extremities of each retort being furnished with suitable closing appliances, by which they may be tightly closed, and the upper extremity being provided with a tube, through which the gases generated in the retort may have exit, and the lower extremity having a suitable tap-hole, through which any reduced and melted metal may be run from the retort, in the manner substantially as shown in the accompanying drawings, and as hereinafter specified and set forth.

Second, it also consists, in an apparatus or kiln for subjecting ores to the chemical and comminuting action of gases resulting from the destructive distillation of bituminous coal or other carbonaceous matters, in the combination of a series of retorts for containing the ore to be treated ranged on either side of the central fire-box of the kiln in the fire-chamber of the same, a supplemental retort for holding the carbonaceous matter to be distilled extending through the fire-chamber from one end of the kiln to the other, directly over the fire-box, and conduits connecting the said supplemental retort with each of the ore-retorts

ranged on each side of the fire-box, the supplemental retort serving for the distillation of the carbonaceous matters, and also for the deflection of the heat and flames of the fire against and around the ore-retorts, and the conduits serving to convey the generated gases from the supplemental retort to the ore-retorts, substantially as shown in the accompanying drawings, and as hereinafter specified and set forth.

Third, it also consists, in a kiln for subjecting ores to the action of gases resulting from the destructive distillation of bituminous coal or other carbonaceous matters, in the combination, with the retorts for holding the ore, of conduits tapping each of the said retorts at its extremity opposite to that at which the gaseous distillates are introduced into the retort, or in which the carbonaceous matters to be distilled are contained, and between which end and the point of juncture of the conduit with the retort, the ore to be treated is contained in the retort, the conduit serving to lead the gases from the retorts to the fire-chamber, there to be burned to assist in heating the retorts, substantially as shown in the accompanying drawings, and as hereinafter specified and set forth.

Fourth, it further consists, in a kiln for subjecting ores to the action of gases resulting from the destructive distillation of bituminous coal or other carbonaceous matters, in the combination, with the retorts for holding the ores to be subjected to the action of gases, and arranged so that they may be tightly closed at their lower and upper extremities, of conduits provided with the weighted valves leading from the upper extremities of the retorts downward on the outside of the kiln to and terminating in tuyeres which lead into the fire-chamber, each and all being arranged and combined substantially as shown in the accompanying drawings, and as specified and set forth and claimed herein.

The operation consists in charging into each of the retorts, first, a quantity of bituminous coal or other carbonaceous matter, from which gaseous hydrocarbons may be distilled by heat, and upon such bituminous coal or other carbonaceous substance a quantity of the ore to be treated, so as to disintegrate, separate, or resolve the same into small or minute parts, or such ore and carbonaceous matter may be

charged into the retort mingled together. The charging, as aforesaid, having been completed, the mouth or upper extremity of the retort is firmly closed, and the fire in the fire-box of the said furnace or kiln is started in the usual manner of commencing fires in furnaces. As soon as the contents of the retorts become sufficiently heated the hydrocarbons are distilled from the coal or carbonaceous matter aforesaid, which, in their heated condition, and more or less under pressure, may be regulated, as hereinafter described, exerts a chemical, reducing, and disintegrating, and resolving and separating action upon the heated ore with which it is in contact in the retort. The gaseous hydrocarbons after having acted on the ores flow through the conducting-pipe to the fire-chamber and are burned in the same to assist in heating the said retorts. The ore having been long enough subjected to the action of the heated gases and pressure thereof, the lower ends of the retorts are opened and the charges in the same are removed therefrom. The coke resulting from the distillation of the coal or carbonaceous matters may be used as fuel in the fire-chamber of the furnace or kiln aforesaid.

In the drawings, in the figures of which similar parts are indicated by the same letters, are shown several arrangements substantially embodying my invention.

In Figure 1 is shown a vertical transverse section of a furnace or kiln and retorts having an oblong, rectangular, horizontal cross-section, substantially as shown in Fig. 2, which is a horizontal section of Fig. 1 above the supplemental retort. Fig. 3 is an end elevation of a furnace or kiln having the same general construction as that of which Figs. 1 and 2 are sections. It contains a central fire-box, F, extending from front to rear or from end to end of the furnace or kiln, having the ash-pit P beneath it, and vertical ore-retorts R R, &c., on each side of the central elongated fire-chamber, the upper extremities of which extend through and project above the top of the said furnace or kiln, and are furnished with means for closing the same tightly, consisting of the caps c, plates p, and clamps l, such as are ordinarily used for the purpose, in connection with gas-retorts, man-holes, and similar structures, and the lower extremities of which pass with a curve through the side walls of the furnace or kiln and are closed by the plates and bolts p'. A supplemental retort, R', is supported horizontally directly above the fire-chamber or fire-box F by the fire-brick arches B B and the end walls of the said furnace or kiln, through which it projects. The extremities of the supplemental retort R', projecting through the walls of the furnace or kiln, are each furnished with a cap and clamp for tightly closing them upon the said outer ends of the retorts, as shown in Fig. 2. The supplemental retort communicates with the lower ends of the ore-retorts, on each side of the same, through the mains M and the branching conduits, tubes, or pipes a.

Leading from the upper extremities of the ore-retorts to gas holders or chambers H, located adjacent to the fire-box F and ash-pit P, and partially beneath the fire-chamber of the said furnace or kiln, are the gas-conducting tubes or pipes d, containing each a cock, e, for conducting the hydrocarbon gases from the retorts to the gas-holders H, whence they are led by suitable conduits or tubes f, shown in Fig. 3, into the ash-pit, from which, mingled with air entering through the door E, they are drawn by the draft through the fire-grate, and are burned to assist in heating the retorts and the ore therein contained.

The gas-holders or receiving-chambers H are constructed with an outer and inner casing, with an air-space, i, between the two, excepting toward the fire box or chamber of the furnace or kiln, for the purpose of retaining the hydrocarbon gases in the heated condition in which they leave the ore-retorts R, and they are located adjacent to the fire-box or fire-chamber, so that the gases may receive additional heat from or be kept hot by the same. The space i might be filled with any non-conducting substance, and the conducting pipes or tubes d ought to be covered with a non-conducting substance, so as to retain the heat therein.

The fire-box or fire-chamber F and the ash-pit P are respectively furnished at each end of the furnace or kiln with doors D and E, as shown in Fig. 3, which may be regarded as an elevation of either end of said furnace or kiln, as the same are substantially alike in all respects of construction and operation.

In Fig. 3 the tubes or pipes a, branching from the gas-mains M, enter the retorts R in a somewhat different manner from that shown in Figs. 1 and 2—viz., through the upper half of the plates p', closing the lower ends of the retorts—instead of through the tops of the portions of the said retorts protruding through the walls of the said furnaces or kilns.

In Fig. 3 the plates p' are divided into halves horizontally, the upper halves of which are bolted to the mouths or openings of the said retorts, and through them the branching conduits, tubes, or pipes a pass; but the lower halves are held in place by clamps, and may be easily removed. Each of the caps p' closing the lower ends of the said ore-retorts, has a small tap-hole, n, Fig. 1, through which may be drawn any reduced and melted metal or other matter, should there be any such, resulting from the action of the gases and the heat on the ore in the said retorts R.

Fig. 4 shows a side elevation of a kiln substantially the same as that illustrated in Figs. 1, 2, and 3, with the exception that the tubes or conduits d for conducting the gases from the upper extremities of the said ore-retorts open directly into the fire-chamber through tuyeres t, piercing the side walls of the same, instead of communicating with it through said gas-holders or receiving-chambers H and the ash-pit P, as in Figs. 1 to 3, inclusive. The gas pipes or tubes d in Fig. 4 are each pro-

vided with a weighted valve, *v*, by which the pressure of the gases in the said ore-retorts may be varied as desired by moving the weight on the lever nearer to or farther from the fulcrum. A section of the tubes or conduits *d* of Fig. 4, including the tuyeres *t* and valve *v*, is shown in Fig. 5.

Fig. 5 is a vertical cross-section of a furnace or kiln and retorts in which the supplemental and horizontal retort *R'*, being elliptical in cross-section, is placed with the major axis of its cross-section vertical instead of horizontal, as in Figs. 1 to 3, inclusive, which permits the same width of furnace or kiln, or, rather, of space, between the two opposite lines or rows of said ore-retorts—a supplemental retort of a greater cubical capacity. In this arrangement, also, the supplemental retort *R'* communicates with the ore-retorts *R* by tubes or conduits contained entirely in the fire-chamber of the furnace or kiln. The gas-conducting tubes *d*, for conveying the gases from the retorts *R* to the fire-chamber, communicate with the chamber through tuyeres *t*, piercing the side walls of the chamber, each of which has an air-tube, *o*, extending into it from the atmosphere and serving to admit air into the chamber, which is mingled with the gases flowing through the tube *d*, for the combustion of the same. The air-tubes *o* of the tuyeres may be provided each with a valve, slide, or other means by which the amount of air admitted through it may be proportioned to the quantity of gas passing through the tuyeres.

In Fig. 6 is shown a horizontal cross-section of a modification of my invention, in which there is no supplemental ore-retort, and in which the gases for the treatment of the ores are generated in the ore-retorts themselves. The absence of the supplemental retort allows of the lessening of the width of the fire-chamber or fire-box, the bringing of the opposite rows of retorts nearer together and more directly over the fire-box or fire-chamber, and thus of effecting a greater concentration of heat around the same.

A series of furnaces or kilns of the description shown in cross-section in Fig. 6 may be used in combination with one or a series of furnaces or kilns for the destructive distillation of the carbonaceous matters connected with the retorts of each of the series of ore-furnaces or kilns, and of sufficient capacity to furnish sufficient gas for all of the furnaces or kilns, the retorts of which would be exclusively filled with the kind of ore to be treated, as aforesaid.

In Figs. 7 and 8 is shown another modification of my invention, in which the furnace or kiln is circular in form, Fig. 7 being a vertical and axial section, and Fig. 8 a partial cross-section of the furnace or kiln along the broken line *xx*, Fig. 7. In this modification the case *S* of the said kiln is circular, the fire-box is circular, and the several ore-retorts *R*, which are straight, are arranged in a circle in the fire-chamber around the fire-box. The upper extremities of the retorts project through the top

of the fire-chamber for charging purposes, and for discharging purposes through the annular bottom of the same contained between the circular fire-box *F* and the case *S* of the fire-chamber. The upper and lower extremities of the retorts are closed by plates and clamps, as hereinbefore described.

Projecting from the top of the furnace or kiln proper is the circular dome *S'*, contained within the circle of the ore-retorts *R*, and the interior of which forms a continuation upward of the fire-chamber proper. Within the dome *S'* is contained the cylinder or retort *R''*, whose upper head or end plate is also that of the dome, and between which and the shell of the dome is an annular space, *Z*, through which and around the cylinder *R''* the heated gases from the fire-chamber below flow to the flue *N*. In the top of the retort *R''* is a door, *L*, for charging the same, and at the side, near the bottom, the passage extending to the exterior of the dome *S'*, and furnished with the door *Q*, furnish means for withdrawing the contents of the ore-retort. The upper extremity of each of the lower retorts, *R*, communicates with the upper retort, *R''*, near the bottom of the same, by a short tube, *a'*, through which the gases flow from the former to the latter. These gases having passed up through the retort *R''* and acted upon the ore in the same, are led by gas-conducting pipes *d* and tuyeres *t* into the annular space between the retort *R''* and the shell of the dome *S'*, and then burned to aid in heating the said retort. The lower retorts, *R*, are for holding the carbonaceous matters from which the gases are to be distilled, and also some of the ore to be treated, and the upper retort, *R''*, is designed to hold ore alone, for the purposes of disintegration, separation, or reduction of the same. The treatment of the ore in the upper retort may be final or it may be only preparatory to a further treatment in the retorts below, according to the character or kind of ore treated or the results desired to be obtained.

In the case of the furnaces or kilns shown in Figs. 1 to 6, inclusive, the walls consist of an iron casing and of a fire-brick lining with an air-space between the two, and this might also be the construction of the walls of the furnace or kiln shown in Figs. 7 and 8, which, as shown, however, consist only of a thin shell. All of the said furnaces or kilns are each provided with suitable flue-openings, *N*, into the fire-chamber at or near the top thereof, for carrying off the products of combustion.

The method of using the above apparatus is substantially and briefly as follows—that is to say: The retorts *R* aforesaid being empty and closed at their lower extremities by means of suitable doors or coverings, are charged, or in part filled or supplied through and by their upper extremities or ends, first, with a proportion of the coal or carbonaceous matters from which the gases are to be distilled; and, second and thereafter, with the kind of ore to be treated, substantially as aforesaid. After the comple-

tion of the charging aforesaid the tops of the retorts are tightly closed by the plates *p*, held by the bails or the clamps *l*. The supplemental retort *R'* is charged with the coal or carbonaceous matter and then its ends tightly closed by their plates and clamps. Then, if not already done, the fire is started in the fire-box or fire-chamber of the said furnace or kiln and urged so as to heat and keep at a very high temperature the said several retorts and their contents, the fuel used being, in part at least, coke, resulting from previous workings of the furnace or kiln. Under the influence of the heat hydrocarbon and other gases are distilled from the carbonaceous matters in the several retorts *R*, and also in the supplemental retort *R'*, which, flowing in a very highly-heated condition among, into, and through the heated ore in the said retorts *R*, exercise chemical, disintegrating, and comminuting actions upon the same. The gases, after having passed through the ore, then being treated as aforesaid are led by the gas-conducting tubes *d* back into the fire-chamber, and are there burned to assist in heating the several retorts. Any metal that may be reduced and melted in any of the retorts will flow to the bottom of the same and may be drawn off through the lamp-holes *n*. The ore having been subjected to the action of the highly-heated gases sufficiently long, the plates *p'* are removed from the lower ends of the retorts and their contents or charges withdrawn in a completed condition. The retort *R'* is also relieved and emptied, unless it contains sufficient undecomposed or but partially-decomposed coal for another charge of ore to be treated as aforesaid. The several retorts may now be recharged, substantially as above described, and the operation repeated with a second batch of the kind of ore to be treated, and thus the operation is continued from time to time indefinitely.

The above is, of course, descriptive of the method or operation of said furnace or kiln as carried on when the supplemental retort *R'* is used, substantially as shown in Figs. 1 to 5 of the said drawings, inclusive.

In the case of the furnace or kiln shown in cross-section in Fig. 6, and which contains no supplemental retort *R'*, the several retorts *R* are charged or supplied with coal and ore substantially as above described, but with a greater proportion of coal, owing to the absence of the supplemental retort and the gases that would be furnished thereby, and the operation and manipulation for disintegrating, separating, and reducing ores is substantially the same as above described, excepting as modified by the absence of the supplemental retort.

In the apparatus shown in Figs. 7 and 8 the lower retorts, *R*, are charged or supplied with coal or other carbonaceous matter for the distillation of gases and treating of ore, as aforesaid, and the upper retort or cylinder, *R'''*, with ore alone. The gases generated in the said several retorts *R*, having acted on the said ore in the same, flow into the retort *R'''*, and there

act upon the ore in it, and thence flow back into the dome *S'* through the tubes or conduits *d*, and are there burned, to aid combustion and to assist in heating the retort *R'''*. There may be as many charges worked in the upper retort as in the lower ones, *R*, or two or more charges may be treated in the lower retorts to one in the upper one, *R'''*, in which the latter would be subjected to the action of the gases generated in the lower retorts, *R*, from the two or more charges worked therein. Again, the treatment of the ore in the upper retort may be preparatory to a second treatment of the same in the lower retorts, and so on.

It is to be observed that in my apparatus the distillation of the carbonaceous matters for the production of the gases and the heating of the ore subjected to the action thereof are effected by the same fire, there being but one fire-box or chamber of combustion and but one fire in the furnace or kiln to accomplish the two results.

I would further point out that by the use of a number or series of retorts of comparatively small cross-section, I obtain a greater heating-surface and a higher and more uniform temperature through the mass of the ore than would be the case were the same amount of ore contained in one large retort or furnace and subjected to the heat of the same fire.

Having described my invention, I claim and wish to secure by Letters Patent—

1. The within-described apparatus for subjecting ores to the chemical and comminuting action of the gases resulting from the destructive distillation of bituminous coal or other carbonaceous matters, consisting of a series of approximately-vertical retorts for holding the carbonaceous matters from which the gases are to be distilled, and the ores to be subjected to the action of the same ranged in the fire-chamber of a kiln on each side of a central fire-box, each of the said retorts projecting through the roof of the kiln and passing with a curve through one of the side walls of the same, near the bottom of the fire-chamber, the upper and lower extremities of each retort being furnished with suitable closing appliances by which they may be tightly closed, and the upper extremity being provided with a tube, through which the gases generated in the retort may have exit, and the lower extremity having a suitable tap hole, through which any reduced and melted metal may be run from the retort, substantially as specified.

2. In an apparatus or kiln for subjecting ores to the chemical and comminuting action of gases resulting from the destructive distillation of bituminous coal or other carbonaceous matters, the combination of a series of retorts for containing the ore to be treated, ranged on either side of the central fire-box of the kiln in the fire-chamber of the same, a supplemental retort for holding the carbonaceous matter to be distilled extending through the fire-chamber from one end of the kiln to the other, directly over the fire-box, and conduits connect

ing the said supplemental retort with each of the ore-retorts ranged on each side of the fire-box, the supplemental retort serving for the distillation of the carbonaceous matters, and also for the deflection of the heat and flames of the fire against and around the ore-retorts, and the conduits serving to convey the generated gases from the supplemental retort to the ore-retorts, substantially as specified.

10 3. In a kiln for subjecting ores to the action of gases resulting from the destructive distillation of bituminous coal or other carbonaceous matters, the combination, with the retorts for holding the ore, of conduits tapping each 15 of the said retorts at its extremity opposite to that at which the gaseous distillates are introduced into the retort, or in which the carbonaceous matters to be distilled are contained, and between which end and the point of juncture of the conduit with the retort the ore to 20 be treated is contained in the retort, the conduits serving to lead the gases from the retorts to the fire-chamber, there to be burned to

assist in heating the retorts, substantially as specified.

4. In a kiln for subjecting ores to the action of gases resulting from the destructive distillation of bituminous coal or other carbonaceous matters, the combination, with the retorts for holding the ores to be subjected to the action of the gases and arranged so that they may be tightly closed at their lower and upper extremities, of conduits *d*, provided with the weighted valves *v*, leading from the upper extremities of the retorts downward on the outside of the kiln to and terminating in the tuyeres *t*, leading into the fire-chamber, substantially as specified.

In testimony whereof I have, on this 14th day of February, A. D. 1881, hereunto set my hand.

S. MORRIS LILLIE.

In presence of—

JAMES L. ANDEM,
B. F. STEIGER.
